UNITED STATES PATENT OFFICE.

JOHN FREDERICK FORTH, OF NEW YORK, N. Y.

TOBACCO-PIPE CLEANER.

SPECIFICATION forming part of Letters Patent No. 690,717, dated January 7, 1902.

Application filed October 7, 1901. Serial No. 77,839. (No model.)

To all whom it may concern:

Be it known that I, JOHN FREDERICK FORTH, a subject of the King of Great Britain, and a resident of New York city, New York, have 5 invented certain new and useful Improvements in Tobacco-Pipe Cleaners, of which the following is a specification.

My invention relates to a tobacco-pipe cleaner, and has for its object to produce one which 10 shall be cheap and efficient. It is necessary with these devices that they should have a certain degree of stiffness to enable them to be readily inserted in the stem of the pipe and yet have sufficient flexibility to follow any 15 irregularity readily and to permit them to be coiled easily and brought back into shape for insertion with facility. As they must be sold at a very low price, it is of the utmost importance that they be cheaply constructed. 20 This is particularly so because they are generally thrown away after a single use. Some attempts have been made to produce these articles—one consisting of a piece of hemp cord or other loose cord stiffened for a part 25 of its length by shellac. The objection to this has been that it is apt to get lumpy and bend, so that it will fail to pass through. Another form has consisted of a wire core with a braided covering of fibrous material, the 30 core being wrapped around the end of the braid. This was effective in some degree, but unduly-costly to make, and the braided covering was apt to slip on the wire. In addition, it could only be passed through the pipe in one 35 direction.

The improved form of the device which I have invented admits of being reciprocated in the pipe-stem and is at the same time exceedingly cheap and effective. It consists, 40 in general, of a center or core of absorbent material inclosed in braided or twisted wires. For absorbent material I prefer to use paper, which may be plaited, folded, or twisted; but by preference it is folded, inasmuch as the 45 wires furnish the necessary stiffness for its use in this form. A small portion of the end

of the cleaner may be left uncovered, so that the paper will form a little brush, assisting in cleaning the tube.

The accompanying drawing shows a pipe-cleaner constructed according to my invention.

In the drawing, A is the core of absorbent material. As before stated, I prefer paper; but other substances might be used, provided 55 they are sufficiently absorbent. As indicated in the drawing, the core is formed by folding the paper. The wires B are braided about it, pressing it to the form shown in the drawing. A small portion A' of the paper or other 60 fibrous substance is left uncovered and forms the brush already referred to. The brush A' might, if desired, be omitted, although this would not be so good a construction. Nevertheless the cleaner would be efficacious, the 65 scraping or rasping of the wires over the accretions in the pipe-stem removing them very well, although the operation is more perfect with the brush A'.

Having thus described my invention, what 70 I claim, and desire to protect by Letters Patent of the United States, is—

1. A tobacco-pipe cleaner comprising a center or core of absorbent material, having wires plaited or twisted over substantially the en- 75 tire outside thereof.

2. A tobacco-pipe cleaner comprising a core of folded paper having wires plaited around substantially the entire outside thereof.

3. A tobacco-pipe cleaner having a center 80 of folded paper with wires plaited around substantially the entire outside thereof, a portion of the paper being uncovered so as to form a brush.

In witness whereof I have hereunto set my 85 hand, this 4th day of October, in the year 1901, in the presence of two witnesses.

JOHN FREDERICK FORTH.
